UNITED STATES PATENT OFFICE.

EDWARD E. STEVENSON, OF LOS ANGELES, CALIFORNIA, ASSIGNOR, BY MESNE ASSIGNMENTS, TO EMSCO DERRICK & EQUIPMENT COMPANY, OF LOS ANGELES, CALIFORNIA, A CORPORATION OF CALIFORNIA.

PUMP-ROD SUSPENSION DEVICE.

Application filed October 5, 1926. Serial No. 139,620.

This invention has to do generally with devices for suspending pump rods from the walking beams whereby they are adapted to be reciprocated, and has as its principal object to provide a device of extreme simplicity whereby the variable angularity between beam and rod is compensated to a very large degree so the pump or polish rod reciprocated thereby may be maintained substantially vertical or have straight-line motion rather than having appreciable inclination from the vertical during its reciprocation.

The desirability of compensating the variable angularity of the beam, and thus reducing rod-bending to a minimum, is very well understood by those skilled in the art, though it may be here briefly mentioned that bending of the rod is harmful in that it tends to over-stress the rod and stuffing box through which it reciprocates, and the binding action occurring between a bent rod and its stuffing box causes rapid and undue wear both of the rod and box. Generally, it may be considered as lowering the general efficiency of the pump apparatus and as reducing the extent of its useful life materially.

Many different devices have been arranged to accomplish the desired result, most of them depending upon more or less complicated connections between the beam and a stationarily located point on the derrick structure or between the beam and rod hanger. The complications and resulting unreliability of such mechanisms generally defeat their purpose, for service conditions in oil fields are most severe and many of the operators are unequipped properly to care for and make the necessary adjustments of the devices.

I have therefore devised a very simple compensating device, the compensation being gained by the peculiar nature and relative arrangements of the hanger elements, rather than by the interposition of mechanism between a hanger and its associated beam. By virtue of its simplicity, the device may be made, applied and cared for at minimum cost, and may be so sturdily constructed, without being over bulky or of excessive weight, that it is well adapted to stand up under severe service conditions.

Generally, the device may be described as an articulated hanger or stirrup depending from the beam. The stirrup is so applied to the beam and to the polish rod that its jointed action during reciprocation of the beam maintains the point of rod or load application substantially in vertical alignment with the stuffing box through which the rod reciprocates, all to the ends enumerated above.

A better understanding of the invention, its advantages, features of novelty and objects will be had from the following specification, reference being had to the accompanying drawings in which:

Fig. 1 illustrates an embodiment of my invention applied to a conventionally illustrated pump operating mechanism;

Fig. 2 is an enlarged fragmentary view of my device in the position it preferably assumes when the walking beam is substantially horizontal;

Fig. 3 is a view of Fig. 2 looking from the right thereof;

Fig. 4 is a fragmentary top plan view of Fig. 2;

Fig. 5 is a view similar to Fig. 2 but showing the relative position of parts when the walking beam is rotated in opposite directions out of the position of Fig. 2;

Fig. 6 is a detached plan view of the beam or crown-casting;

Fig. 7 is a side elevation of Fig. 6;

Fig. 8 is an elevation of the upper eye-casting preferably provided at the ends of the pendant hanger links;

Fig. 9 is a side elevation of Fig. 8;

Fig. 10 is an elevation of one of the eye-castings preferably applied to the lower ends of the hanger links;

Fig. 11 is a side elevation of Fig. 10;

Fig. 12 is an elevation of one of the transverse links of the device;

Fig. 13 is a section on line 13—13 of Fig. 12;

Fig. 14 is a top, plan view of the cross-head or bridging element of my device;

Fig. 15 is a front elevation of Fig. 14; and

Fig. 16 is a section on line 16—16 of Fig. 15.

Generally described, my invention embodies a stirrup or hanger made up of a pair of pendant, rod-suspension links supported

by the beam and connected at their lower ends by a transverse rod-supporting link to which the rod or load is, in effect, applied through a pivotal joint; the points of pivotal connection between the links and rod being arranged in angular relation. My broader claims are directed to such a combination, that is, a combination wherein only a single pair of pendant, rod-suspension links and a single transverse rod-supporting link is employed, for it will be readily understood that such elements and arrangement are self-sufficient to accomplish the desired end. However, as a practical feature, I provide a duplicate stirrup assembly or set of linkage at each side of the walking beam and connect the two transverse links by a cross-head to which the rod is adapted to be applied, the head having pivotal connection with the two transverse links. By reason of this symmetrical arrangement, the strains are more effectively taken and distributed and connection with the pump rod is made more readily. It is not to be construed, however, that my broader claims are in any sense limited to this duplication and interconnection of hanger members.

In Figs. 1 and 2 numeral 10 designates a usual walking beam pivotally mounted on Samson post 11 and adapted to be oscillated in the usual manner through crank mechanism generally indicated at 12. The forward end of beam 10 is preferably forked in the usual manner, as indicated at 13, open-ended slot 14 being substantially in vertical alinement with the stuffing box 15 through which polish or pump rod 16 extends to the well generally indicated at 17, it being understood that polish rod 16 is adapted to be connected in the usual manner through a string of sucker rods (not shown) to a pump plunger (not shown).

Numeral 18 generally designates the hanger which is the subject-matter of the present application and which forms a driving connection between beam 10 and rod 16 whereby said beam is adapted to reciprocate rod 16 or at least lift said rod, since descention of the rod is ordinarily accomplished solely through gravitation, the connection between the hanger and polish rod being such that they are capable of relative longitudinal movement during the downstroke so, in the event descention of the rod is unduly resisted from beneath, the beam and hanger may continue their downstroke without injuring the hanger or the rod and its associated elements.

The two sets of linkages are designated individually as 19 and 20, they being suspended from opposite sides of beam 10 by the common crown block 21 (Figs. 4 and 6). As viewed in plan, this block is forked, the fork arms 22 being adapted to rest on the forked end of the beam, and slot 23

being disposed over slot 14 so the pump rod may pass upwardly therethrough should occasion demand. Bolts 24 serve to anchor the block to the beam.

Block 21 carries horizontal trunnions 25 and 26 and extending from one side thereof, and trunnions 25^a and 26^a from the other side; trunnions 25 and 25^a being in axial alinement, as are also trunnions 26 and 26^a. Preferably, though not necessarily, block 21 is so fashioned and so located on the beam that when the latter is approximately horizontal (Fig. 2) trunnions 25 and 26 are not only substantially in horizontal alinement but are also substantially equi-spaced from the extended axis of rod 16.

Since the two linkage sets are identical, only one need be described in detail, parts of linkage 20 which are similar to parts of linkage 19 being designated by similar reference numerals but with the exponent "a." Preferably, though not necessarily, pendant, rod suspension links 27 and 28 are of equal length and are in the form of rigid straps having eyecastings 29 and 30 at their opposite ends. However, the word "link" as here applied to the pendant members 27, 28 and as used in the claims with reference to these members, is used merely to distinguish "tension elements" between the beam and the "third" link hereinafter mentioned, and they need not necessarily be rigid. Therefore, my claims are not to be considered as limited to connecting elements which are rigid. Castings 29 are pivotally mounted on trunnions 25 and 26, being retained by such means as cotter keys 31, the straps extending downwardly, and preferably, though not necessarily, inwardly toward the transverse connecting link 32.

The "third" or rod-supporting link 32 is preferably, though not necessarily, triangular (Fig. 12) and is adapted to take pins 33 and 34 whereby links 27 and 28, respectively, are pivotally connected through their eyecastings 30 to said link 32, cotter keys 35 or other suitable means being employed to hold the pivot pins and eye-castings from displacement. It will be seen that links 27, 28 and 32 are pivotally movable through substantially parallel planes.

Cross-head 36 connects links 32 and 32^a of sets 19 and 20, respectively, and is adapted to take rod 16. While head 36 may be of any suitable formation, I have shown a preferred construction in Figs. 14, 15 and 16. Body portion 37 carries axially alined trunnions 38, 39 adapted to be taken pivotally in links 32 and 32^a, respectively, annular shoulders 40 and cotter keys 41 engaging the inner and outer sides, respectively, of the links to hold the elements in assembly.

Body member 37 has a medial, vertically extending rod-receiving way 42 which opens to the side thereof, the axis of said way pref-

erably, though not necessarily, lying in the common vertical axial plane of trunnions 38, 39. Any suitable releasable closure means may be provided for retaining rod 16 in way 5 42, but I have illustrated preferred means in the form of a gate 43 pivoted at 44 at one side of the way and adapted to be swung through sockets 45 across the way, as illustrated in full lines in Fig. 14, a keeper pin 46 being 10 dropped through lugs 47 to hold the gate releasably in closed position.

Rod 16 has a downwardly facing, annular shoulder adapted to rest on top body member 37 when the rod is within the way. This 15 shoulder 48 (Fig. 3) is conveniently, though not necessarily, formed by the lower end of usual rod-clamp 49, said clamp being adjustable longitudinally along the rod and being held in adjusted position by clamp 20 screws 50. The rod and its load are thus applied to links 32, 32' through head 36, and the latter has pivotal connection with said links through trunnions 38, 39. It will be immediately apparent that with gate 43 25 swung to open position (dotted lines in Fig. 14) the hanger, as a whole, may be swung about the trunnions on casting 21 towards or away from the polish rod and thus move head 36 into or out of rod engaging position.

30 In setting forth the following relative positions of pivot points, etc., mention need be made of only one set of linkage, for it will be apparent the two sets are similar throughout and that, with the polish rod pivotally applied to one, only, of the transverse links, one set of linkage, alone, is competent to perform the functions ascribed to the pair of inter-connected linkage sets.

I also make the reservation that while I 40 will hereinbelow set forth relative positions of pivot points, etc., which give particularly good results, these relative positions may be varied within reasonable limits without departing from the spirit and scope of my invention, considered in its broader aspects, and therefore only such claims as specify 45 particular relationships are to be considered as limited to such relationships.

In pointing out these relationships it will 50 be helpful to consider the beam in the approximately horizontal position of Fig. 2, though certain of the relationships change and others are constant when the beam moves out of horizontal.

55 Pivot points 25 and 26 are in horizontal alinement and are equi-spaced from the extended axial plane of rod 16, pendant links 27 and 28 are of substantially equal length and incline inwardly to trunnions 33 and 34, 60 respectively, which trunnions are also in horizontal alinement and equi-spaced from the axis of rod 16. Trunnion or pivot point 38 is between and below trunnions 33, 34 and equi-spaced therefrom, the angle "a"

(Fig. 12) included between axial planes 65 common to trunnion 38 and the individual pivot pins preferably, though not necessarily, being approximately 90°. It will be seen that the rod is applied, in effect, to link 32 at a point which is axially offset from trunnions 70 33 and 34.

With the above relationships existing and with a downbearing load applied to the cross-head, or, in effect, to link 32, upward movement of beam 10 (see full lines in Fig. 75 5) draws heads 36 upwardly against clamp 49 and thus lifts rod 16, trunnion 38 being controlled by the linkage so it travels through a substantially vertical path approximately coincident with the extended 80 axis of the rod, there thus being practically no tendency toward bending rod 16.

As beam 10 descends (see dotted lines in Fig. 5) rod 16 gravitates, normally holding shoulder 48 in contact with the upper face 85 of cross-head 36. During the descension of the beam, the linkage controls the movement of trunnion 38 so it travels substantially straight downward. During the up and down strokes of the beam, it will be evident that link 32 moves pivotally about trunnion 38 and that the variable distance 90 between said trunnion and trunnions 25 and 26 (and hence the variable angularity between the beam and rod) is substantially 95 compensated by this pivotal movement.

Thus it will be seen that I have provided a most simple and effective device for insuring substantially straight-line reciprocation of the pump rod, and by duplicating the linkage sets and applying the rod to the common cross-head I am able to provide an installation wherein all strains are efficiently distributed and whereby the device may be 100 engaged with and disengaged from the rod 105 with speed and minimum effort.

Should the pump plunger become "sanded-in" so rod 16 does not gravitate during the descension of the beam, head 36 merely 110 slides down the rod, (the fit of the rod within way 42 permitting this) the upper end of said rod avoiding interference with beam 10 and casting 21 by virtue of slots 14 and 23.

It will be understood the drawings and 115 descriptions are to be considered merely as illustrative of and not restrictive on the broader claims appended hereto, for various changes in design, structure and arrangement may be made without departing from 120 the spirit and scope of said claims.

I claim:

1. In combination with a walking beam and a polish rod, means operatively connecting the beam and rod and including a 125 pair of links pendants supported from points spaced longitudinally along the beam, and a third link, connecting the pendant

- links near their lower ends, the rod being applied, in effect, to the third link at a point axially offset from the connections between the links.
5. 2. In combination with a walking beam and a polish rod, means operatively connecting the beam and rod and including a pair of links pendants supported from points spaced longitudinally along the beam, a 10 third link connecting the pendant links near their lower ends, and a pivotal connection between said rod and third link at a point axially offset from the connections between the links.
15. 3. In combination with a walking beam and a polish rod, means operatively connecting the beam and rod and including a pair of links pendants supported from the beam, a third link connecting the pendant links 20 near their lower ends, and a pivotal connection between said rod and third link; said pivotal connection being between and below the points of connection of the third link with the pendant links.
25. 4. In combination with a walking beam and a polish rod, means operatively connecting the beam and rod and including a pair of links pendants supported from the beam, a third link connecting the pendant 30 links near their lower ends, and a pivotal connection between said rod and third link; said pivotal connection being between the points of connection of the third link with the pendant links; there being an angle of 35 approximately 90° included between lines connecting the pivotal connection and said points of connection of the third with the pendant links.
5. In combination with a walking beam and a polish rod, means operatively connecting the beam and rod and including a pair of links pendants supported from the beam, a third link connecting the pendant links near their lower ends, and a pivotal connection between said rod and third link; said 40 pivotal connection being between, below and equidistant from the points of connection of the third link with the pendant links.
6. In combination with a walking beam and a polish rod, means operatively connecting the beam and rod, said means including two sets of linkage; each set including a pair of links pendants supported from the beam, and a third link connecting the pendant links near their lower ends; and a cross-head connecting the third links of the two sets at points axially offset from the connections between links, said head being 45 adapted to take the rod.
7. In a device for supporting pump rods 50 from walking beams, a pair of links adapted to be supported pendants from points spaced longitudinally along the beam, a third link connecting said pendant links near their lower ends, and a head applied to 55 the third link at a point axially offset from the connections between links and adapted to take a pump rod.

In witness that I claim the foregoing I have hereunto subscribed my name this 8th 70 day of Sept. 1926.

EDWARD E. STEVENSON.
